UNITED STATES PATENT OFFICE.

ROY W. HEATH, OF KALAMAZOO, MICHIGAN.

METHOD OF MAKING DENTAL-PLATE MOLDS AND DENTAL PLATES.

Application filed June 18, 1926. Serial No. 116,880.

The main object of this invention is to provide an improved method of making dental plate molds and dental plates which is well adapted for "roofless" plates.

- 5 A further object is to provide an improved method of making dental plates which results in securing a plate, which effectively retains its position in the mouth and is comfortable for the wearer.
- 10 A further object is to provide an improved method by which dental plates may be properly fitted to the conditions of the individual.

Objects pertaining to details and economies of my improved process will definitely appear from the detailed description to follow. The invention is clearly defined and pointed out in the claims.

- 15 The various steps of my improved process 20 are clearly illustrated in the accompanying drawing forming a part of this application, in which:

Fig. 1 is a top perspective view of a roofless dental plate made in accordance with 25 my improved method.

Fig. 2 is a perspective view of an impression tray of standard type.

Fig. 3 is a perspective view illustrating 30 the first step in preparing the dental tray for taking the impression.

Fig. 4 is a perspective view of the tray as prepared in Fig. 3 with the cast or impression therein.

Fig. 5 is a perspective view of the cast removed from the tray.

Fig. 6 is a plan view of a chart of the diagnosis of the patient's mouth.

Fig. 7 is a cross sectional view of the cast or model as prepared for making the plate.

40 Fig. 8 is a perspective view showing the wax model as formed upon the cast.

It will be understood that the drawings are mainly conventional and are designed to illustrate the steps of my improved 45 method.

In the practice of my improved method a dental tray 1 such as that shown in Fig. 2 is prepared for taking the impression by applying wax indicated at 2 to the flanges 50 of the tray, the wax being molded to build up the flanges and conform them to the interior cheek muscles at the base of the gums. I also preferably build up the rear of the tray at 3 with wax to protect the 55 soft palate.

With the tray thus prepared an impression 4 of plaster of Paris or other suitable material is made in the usual manner, care being taken, however, to take a close impression.

60 Either before or after taking this impression the mouth of the patient is diagnosed to determine the relative degree of hardness or softness of the plate supporting surfaces or mouth tissue. To facilitate the making 65 of this diagnosis and preparing the model therefrom, I find a chart, roughly horseshoe-shaped as indicated in Fig. 6 to be very convenient. On this chart I apply letters such as H indicating "hard"; M indicating 70 "medium"; S indicating "soft" and E S indicating "extra soft", these letters being applied to the chart in the relative relation thereon indicating mouth conditions.

75 The surface of the model is cut away as indicated in Figs. 5 and 7 to a degree corresponding to the degree of softness of the tissue; that is, little if any of the surface of the model is removed where the plate to be formed is to be supported by a relatively 80 hard tissue. The amount removed varies, as stated, in proportion to the degree of softness of the tissue.

85 With the model or cast formed in this way the plate may be formed by the usual or any desirable methods. Experience has shown that the resulting plate is comfortable to the wearer and very effectively maintains its position or remains in position.

Having thus described my invention what 90 I claim as new and desire to secure by Letters Patent is:

1. The method of preparing dental plates consisting of applying wax to the flange of an impression tray and conforming to 95 the interior cheek muscles at the base of the gums, applying wax to the rear edge of the tray and conforming to the soft palate, making a plaster model in the tray thus produced, cutting away the surface of the model 100 in varying degrees corresponding to the degree of softness of the corresponding plate supporting surface, and forming the plate from the model thus prepared.

2. The method of preparing dental plates 105 consisting of applying wax to the flange of an impression tray and conforming to the interior cheek muscles at the base of the gums, making a plaster model in the tray thus produced, cutting away the surface of 110

the model in varying degrees corresponding to the degree of softness of the corresponding plate supporting surface, and forming the plate from the model thus prepared.

- 5 3. The method of preparing dental plates consisting of applying wax to the flange of an impression tray and conforming to the interior cheek muscles at the base of the gums, making a plaster model in the tray
10 thus produced, diagnosing the mouth of the patient to ascertain the relative hardness of tissue in the plate supporting surfaces thereof, cutting away the surface of the model in varying degrees corresponding to the de-
15 gree of softness of the corresponding plate

supporting surface, and forming the plate from the model thus prepared.

4. The method of preparing dental plates consisting of making a model of the mouth, diagnosing the mouth of the patient to ascertain the relative hardness of tissue in the plate supporting surfaces thereof, cutting away the surface of the model in varying degrees corresponding to the degree of softness of the corresponding plate supporting 20 surface, and forming the plate from the model thus prepared. 25

In witness whereof I have hereunto set my hand.

ROY W. HEATH.
